UNITED STATES PATENT OFFICE.

MARTIN MOEST AND RUDOLF MÜLLER VON BERNECK, OF HÖCHST-ON-THE-MAIN, AND JOSEF OPL, OF LORSBACH, GERMANY, ASSIGNORS TO FARBWERKE VORM. MEISTER LUCIUS & BRÜNING, OF HÖCHST-ON-THE-MAIN, GERMANY, A CORPORATION OF GERMANY.

PROCESS OF MANUFACTURING CONCENTRATED NITRIC ACID.

1,050,160.

Specification of Letters Patent. Patented Jan. 14, 1913.

Application filed July 26, 1911. Serial No. 640,647.

To all whom it may concern:

Be it known that we, MARTIN MOEST, Ph. D., RUDOLF MÜLLER VON BERNECK, and JOSEF OPL, chemists, citizens of the Empires 5 of Germany and Austria-Hungary, respectively, the first two residing at Höchst-on-the-Main, Germany, and the third at Lorsbach a. T., Germany, have invented certain new and useful Improvements in Nitric Acid of High Percentage and Processes of 10 Making Same, of which the following is a specification.

By the method, hitherto in use in the manufacture of nitric acid, consisting in 15 causing NO_2 gases to act upon water in presence of oxygen, only a comparatively diluted nitric acid is obtained. Thus with mixtures of nitric oxide and air an acid of only 50-52 per cent. strength is produced. 20 With regard to mixtures of pure nitrogen peroxid gas with oxygen, Foerster and Koch (see *Zeitschrift für angewandte Chemie*, 1908, page 2168) have shown that the highest concentration of nitric acid obtainable 25 is an acid of about 68 per cent. strength, namely the acid of the lowest vapor-pressure. From their experiments and from theoretical considerations the said authors draw the following conclusion:—There is 30 no doubt that the highest concentration of nitric acid obtainable by the action of nitrogen peroxid and excess of oxygen upon water at ordinary temperature, scarcely exceeds 69 per cent. In practice it was not 35 possible to obtain in this manner an acid of a greater strength than 60-62 per cent. This fact is unfortunate, particularly because for industrial purposes there is principally required an acid of 70-80 per cent. strength 40 for the preparation of the "mixed acid" mostly used for nitrating purposes, whereas nitric acid of a percentage strength below 70 is employed only to a comparatively small extent. In consequence of this there 45 have been elaborated of late numerous processes for the concentration of the dilute nitric acid obtained from oxids of nitrogen

by their action upon water in presence of excess of oxygen. These processes are however for the most part complicated and in 50 any case expensive.

Now contrary to the technical and theoretical considerations hitherto entertained, we have found a process for manufacturing directly from nitrogen peroxid (or nitrogen 55 tetroxid), water and oxygen at ordinary atmospheric pressure, a nitric acid containing 70 per cent. and more of HNO_3 . This process, which constitutes our present invention, consists in enriching nitric acid obtained in 60 the usual manner, for instance acid of 60-62 per cent. strength, with nitrogen peroxid, which easily dissolves in the acid, and in then subjecting this nitric acid containing nitrogen peroxid, in a finely subdivided 65 state to the action of oxygen. In consequence of the increased concentration of the NO_2 the speed of the reaction is increased in the sense of the equation 2 $\text{NO}_2 + \text{H}_2\text{O} \rightarrow \text{HNO}_3 + \text{HNO}_2$ while at the 70 same time the evaporation of HNO_3 , which is antagonistic to the concentration, is checked by avoiding a considerable excess of oxygen. The non-oxidized part of the nitrogen peroxid or of the nitrous acid, that 75 may be present in solution, is expelled by the oxygen introduced at the end of the reaction system, so that the nitric acid finally obtained is practically free from 80 nitrous acid.

For carrying out our new process it is advantageous to use a system adapted to fulfil the following conditions:—The first part of the system produces a nitric acid of about 50-64 per cent. strength in the usual 85 manner by the action of nitrogen peroxid gases upon water in presence of oxygen; in the second part of the system this nitric acid is enriched with nitrogen peroxid by the introduction of either liquid or gaseous 90 nitrogen peroxid (nitrogen tetroxid) while simultaneously, if required, introducing oxygen; in the third part of the system oxygen is introduced for the purpose of con-

verting nitrogen peroxid into nitric acid and expelling the unused oxids of nitrogen. In practice it is advantageous to work on the counter-current principle and continuously 5 in such a manner that at one end of the system water is introduced and at the other end the concentrated nitric acid is drawn off whereas the oxygen and the nitrogen peroxid gases pass in the opposite direction. 10 The several parts of the system may consist of the known "trickling-towers" or of a system of vessels in which, either by means of spraying nozzles, agitators or any other suitable device, the nitric acid containing 15 NO_2 is brought into intimate contact with the oxygen. The nitrogen peroxid or nitrogen tetroxid may be introduced at suitable points either in liquid or vaporous form or mixed with oxygen. It has been found par- 20 ticularly advantageous to introduce the nitrogen peroxid in such a manner that the current of oxygen is passed through liquid nitrogen peroxid whereby exactly regulated quantities of the nitrogen peroxid can be 25 introduced into the reaction system by op- erating at determined temperatures. The oxygen is introduced either exclusively at the end of the system or at several points as required. When starting from nearly pure 30 oxygen and nearly pure nitrogen peroxid in proper proportions, it is possible, as both gases are consumed, to carry on the process in such a manner that at the end of the system only very small quantities of gas 35 escape so that losses owing to entrainment of nitric acid vapors are entirely avoided. In practice, however, it is advantageous to work with a small excess of oxygen which, in order to avoid losses of oxygen is re- 40 introduced into the process by suitable de- vices. It is not necessary to charge the whole system with pure oxygen, but there may be prepared nitric acid of a lower con- 45 centration in the usual manner from NO_2 , water and air, and the dilute nitric acid thus obtained may be further treated, as above indicated, with NO_2 and oxygen; thus a considerable saving of oxygen is 50 effected. Of course it is possible to combine these arrangements.

The accompanying drawing illustrates suitable apparatus for carrying out the process, the figure being a side elevation. The absorption chambers T^1 , T^2 , T^3 and T^4 , in 55 which the nitrogen-oxids are converted into nitric acid with the aid of oxygen and water, are connected with each other by gas- pipes G . In chamber T^1 , the non-oxidized nitric acid gases from the nitric acid are 60 expelled, with the aid of oxygen. The introduction of the water and the dilute nitric acid is effected at H_2O ; that of the nitric-oxids—alone or mixed with oxygen—at

NO_2 ; and of the oxygen at O . These gases flow through the system in the direction in- 65 dicated by the arrows beside pipes G , while the water and the dilute nitric acid pass through the apparatus in the reverse direc- 70 tion, from the bottom of one chamber, through the lifting device, to the top of the next chamber. D^1 , D^2 , and D^3 are devices 75 for lifting the nitric acid loaded with nitric gases. The finished product is discharged from chamber T^1 at B . In the reaction which takes place, two molecules of NO_2 re- 80 quire one molecule of water and half a mole- cule of oxygen. Consequently, there are re- 85 quired for the oxidation of 92 grams of NO_2 into nitric acid 12 liters of oxygen. In prac- 90 tice, a small excess of oxygen is employed so that no nitrogen oxids escape from the ap- 95 paratus, but only oxygen. The initial tem- 95 perature is that of the surrounding air, and as the reaction is attended by evolution of heat, a rise of the tempreture gradually sets in which depends on the radiation and on the quantity of the nitric-oxid used, per time-unit. We have found that the best re- 95 action takes place if 5-10 kg. of nitrogen peroxid per cubic meter of the reaction area and per hour are employed, according to the desired concentration of the acid. If it is intended to prepare a strong acid, less of the nitrogen peroxid should be used than if an acid of a lower strength is desired.

Having now described our invention what we claim is:

1. The process of manufacturing, in a di- rect way, highly concentrated nitric acid, 100 which consists in enriching the dilute nitric acid, obtained in the usual manner, with nitrogen peroxid and treating this mixture with oxygen.
2. The process of manufacturing, in a di- rect way, highly concentrated nitric acid, 105 which consists in enriching the dilute nitric acid, obtained in the usual manner, with nitrogen peroxid in a gaseous form, and treating this mixture with oxygen.
3. The process of manufacturing, in a di- rect way, highly concentrated nitric acid, 110 which consists in enriching the dilute nitric acid, obtained in the usual manner, with ni- 115 tronogen peroxid which is introduced into the nitric acid in a vaporous form with the aid of a current of oxygen, and treating this mixture with oxygen.
4. The process of manufacturing, in a di- rect way, highly concentrated nitric acid, 120 which consists in enriching the dilute nitric acid, obtained in the usual manner, with ni- 125 tronogen peroxid, and treating this mixture with oxygen, introduced at the end of the reaction-apparatus, thereby expelling the non-oxidized nitric acid gases from the ni- tric acid.

5. The process of manufacturing, in a direct way, highly concentrated nitric acid, which consists in treating dilute nitric acid, obtained in the usual manner, with a mixture of nitrogen peroxid and oxygen and further treating this mixture with oxygen, introduced at the end of the reaction-apparatus, thereby expelling the non-oxidized nitric oxid gases from the nitric acid.

In testimony whereof, we affix our signatures in presence of two witnesses.
